UNITED STATES PATENT OFFICE.

HARRY L. DODSON, OF CHICAGO, ILLINOIS, ASSIGNOR TO E. S. BARNUM,
OF CHICAGO, ILLINOIS.

DESIGN FOR AN ENGINE-FRAME.

SPECIFICATION forming part of Design No. 35,343, dated November 26, 1901.

Application filed November 16, 1900. Serial No. 36,778. Term of patent 14 years.

To all whom it may concern:

Be it known that I, HARRY L. DODSON, a citizen of the United States, residing in the city of Chicago, in the county of Cook and State of Illinois, have invented and produced 5 a new and useful Design for Engine-Frames, of which the following is a specification.

The design is illustrated in the drawings forming a part hereof, in which Figure 1 is a side elevation with one arm partly in section; Fig. 2, a top or plan view; and Fig. 3, a detail, being a cross-sectional elevation of the lower portion of the design.

As shown in the drawings, the leading or 15 important feature of my design consists in a frame or support for mounting engine-cylinders, having diagonally-extending arms A ter-

minating in a cap or overhang B and converging to a common center, having a circular portion forming a journal box or bearing 20 for the crank-shaft of the engine, the whole presenting to the eye the general appearance of the capital letter "Y" with the stem shortened and having a circular central outline and with the caps on its diverging members 25 thrown at an incline from the horizontal.

What I regard as new, and desire to secure by Letters Patent, is—

The design for an engine-frame herein shown and described.

HARRY L. DODSON.
